UNITED STATES PATENT OFFICE.

EDWARD G. WILLIAMS, OF BROOKLYN, NEW YORK, ASSIGNOR TO HIMSELF,
EDWARD R. IVES, OF BRIDGEPORT, CONNECTICUT, AND CORNELIUS
BLAKESLEE, OF BROOKLYN, NEW YORK.

DESIGN FOR A TOY.

SPECIFICATION forming part of Design No. 12,336, dated June 28, 1881.

Application filed February 12, 1881. Term of patent 7 years.

To all whom it may concern:

Be it known that I, EDWARD G. WILLIAMS, of Brooklyn, in Kings county, and State of New York, have originated a new and useful Design for a Toy, of which the following is a specification.

My design is intended for toys of the kind in which are burned compounds known as "Pharaoh's serpents' eggs" and like compounds that will protrude from the toys in burning. Many of such toys, as heretofore made, have been objectionable because of the vulgarity of their designs.

The object I have in view is to produce a design for such a toy which, while it will afford great amusement, shall not be objectionable to the most prudish mind.

To this end my invention consists in a design for a toy intended to be used in burning "Pharaoh's serpents' eggs" and like compounds, consisting in making the toy in the form of an elephant lacking a trunk, and providing it with a receptacle for said eggs or like compounds at the place whence the trunk should extend, so that the eggs or like compounds, in burning, shall protrude and simulate the appearance of a moving trunk.

The accompanying drawing represents a perspective view of a toy embodying my design.

It will be observed that the figure of the elephant lacks a trunk. At A, where the trunk starts, is a receptacle for "Pharaoh's serpents' eggs" or like compounds, and when the latter are ignited the matter which results from their combustion protrudes and winds and twists around like a moving elephant's trunk, thus imparting an appearance of life to the toy.

It is the making of a toy of this kind in the form of an elephant without a trunk which constitutes my design.

What I claim as new, and desire to secure by Letters Patent, is—

A design for a toy intended to be used in burning "Pharaoh's serpents' eggs" and like compounds, which consists of the form of an elephant lacking a trunk, substantially as shown and described.

E. G. WILLIAMS.
